UNITED STATES PATENT OFFICE

GILBERT S. VERNAM, OF HACKENSACK, NEW JERSEY, ASSIGNOR TO INTERNATIONAL COMMUNICATIONS LABORATORIES, INC., OF NEWARK, NEW JERSEY, A CORPORATION OF NEW YORK

AUTOMATIC CONCENTRATION SYSTEM

Application filed December 15, 1931. Serial No. 581,115.

This invention relates generally to printing telegraph exchange systems, and more particularly to such systems in which combination finder-connector switches are employed for establishing a connection in either direction between subscribers' stations and operators' sets equipped for both sending and receiving at a central station.

One of the principal objects of the present invention is to make it unnecessary for a central station operator to recall a subscriber's station when that station has been called and found busy.

Another object is to limit the number of central station operators available to answer incoming calls in accordance with variations in the traffic load.

A further object is to insure the operating efficiency of the system by providing alarms that indicate the location and type of trouble existing anywhere in the system.

In carrying out the objects of this invention, a busy position locator is provided which serves to indicate to a central station operator, who has called a busy subscriber's station, the position of the central station operator in connection with the busy station, and to indicate to the latter operator that the connection with the subscriber's station is not to be released. The calling operator then re-routes the message for transmission by the connected operator. The busy position locator therefore makes unnecessary repeated attempts by a central station operator to establish connection with a busy subscriber's station.

To permit the number of central station operators available to answer incoming calls to be varied in accordance with variations in the traffic load, a make-busy key associated with each operator's position serves, when operated by a supervisor, to make that position busy, and, when released, to make that position idle; while an idle position locator co-operating with the combination finder-connector switches serves to distribute incoming calls to the first idle operator's position. A lamp bank associated with these keys indicates to the supervisor whether the corresponding operators' positions are busy or

idle. It is, therefore, evident that by operating certain make-busy keys, the supervisor can concentrate incoming calls on predetermined operators' positions in accordance with variations in the traffic load. Furthermore, in cases where it is desired to have certain central operators' positions serve as sending positions only, the supervisor, by operating the make-busy keys corresponding to these positions, can concentrate incoming calls on the remaining positions.

To permit the location of trouble that may develop in the system, a number of alarms are provided. One of these alarms is operated when an incoming call remains unanswered for an abnormal period; another is operated when all of the combination switches are busy; another is operated when all of the combination switches are busy and an incoming call is waiting; another is operated when a combination switch has been conditioned for operation but fails to operate completely; and finally another is operated when an operated combination switch fails to release.

Accordingly, one of the principal features of this invention is a busy position locator which enables a calling station operator who has called a busy subscriber's line to ascertain the position of the central station operator in connection with this line.

Another feature consists of a busy position locator, having the above mentioned function, in combination with an idle position indicator adapted to concentrate incoming calls on the first idle central station operator.

An additional feature is a combination finder and connector switch having means for preventing the seizure of a busy switch by an idle position locator and also for preventing the seizure of a switch that has not tested a busy subscriber's line or is connected to a subscriber's line by the busy position locator.

A further feature is the provision of make-busy keys under control of a supervisor for preventing the seizure of any central operator's set by the idle position locator as well as for making any central operator's set a sending position only.

Another feature is the provision of the different types of alarms permitting the identification as well as the location of any kind of trouble occurring in the combination switches.

Other objects and features will become apparent when the following description is taken in connection with the appended claims and with the accompanying drawings, in which:

Fig. 1 illustrates schematically a subscriber's station, a combination line finder and connector switch at a central station together with a supervisor's make-busy key, and the alarms for indicating the existence of trouble in the switches;

Fig. 2 illustrates schematically a central station operator's position equipped for both sending and receiving, and additional alarms for indicating trouble in the switch;

Fig. 3 illustrates schematically an idle position locator;

Fig. 4 illustrates schematically a busy position locator;

Fig. 5 illustrates schematically an alternative form of busy position locator in which a lamp bank at the calling operator's position is used to indicate which other operator is connected to the busy subscriber's line, and

Fig. 6 illustrates the arrangement of the drawings necessary to show the proper relation of the parts of the system.

In order to afford a better understanding of the invention, a general description of the system will first be given. Referring to the drawings, a subscriber's station V is shown connected by a line circuit 1 to a central station. At the central station there is disclosed a combination finder-connector switch W, an idle position locator X (Fig. 3), a busy position locator Y (Fig. 4), and a central station operator's set Z. At the central station are disclosed a supervisor's position U (Fig. 1), having a make-busy key 14 and a lamp 15 individual to each operator's set Z, and alarms S1 (Fig. 1) and S2 (Fig. 2) for indicating the presence of trouble in the system.

Although the parts of the system mentioned have alone been illustrated in the drawings, it is understood that in actual practice, a plurality of subscribers' stations, as V; a plurality of central station operators' sets, as Z; a plurality of combination switches, as W, sufficient to handle any given number of calls between the subscriber's station and the central station operators' sets; and a key, as 14, with a lamp, as 15, for each operator's set would be provided. Moreover, in a system containing a large number of subscribers' stations, it has been found preferable to employ several idle position locators in order to avoid the excessive use to which a single locator would be subjected in such a system.

A general description of the operation of the system at this point will probably aid in understanding the detailed description to follow. Assuming first that a call originates at the subscriber's station V and that the central station operator's set Z is the first idle operator's position, the operation of the system in extending a connection from station V to set Z will be outlined. When the subscriber's station V calls, the idle position locator X (Fig. 3), in a system where but one locator is employed, or the first idle position locator having an idle combination switch associated therewith, in a system where several locators are employed, is started. If the idle position locator X is started, it then selects the combination switch W, after which it causes that switch to be operated until the calling subscriber's line 1 is found. When this occurs the calling subscriber's station V and the central station operator's set Z are interconnected through the switch W. It is to be noted, as mentioned above, that the combination switch W is individual to the central operator's set Z, so that the operation of the switch W invariably connects the calling subscriber's line to the set Z.

When the switch W is selected by the idle position locator X, the lamp 15 at the supervisor's position U is extinguished thereby notifying the supervisor that operator's set Z is busy, and lamp 58 at operator's set Z is lighted to notify the operator at Z that the switch W has started to find a calling line.

When the switch W has found the calling line, the idle position locator X is restored to its normal or home position whereupon it is in readiness to answer the next incoming call. Likewise, when the switch W finds the calling line, the printer motor at the subscriber's station V, which is now connected through the switch W to the operator's set, starts, and the operator's printer is now connected in series with the printer at the subscriber's station. As the printer motor at the set Z is running continuously while the operator is on duty, telegraphic communication between the subscriber and the operator's set can now be carried on. At the end of communication, the operator at set Z releases the connection which stops the motor at the subscriber's station V. The switch W is thereupon released, lamp 58 is extinguished, and the lamp 15 is relighted, indicating to the supervisor that the set Z is again idle.

When the central station operator at set Z desires to establish connection with the subscriber's station V, he dials the number assigned to this station, and thus operates the associated combination switch W to establish connection therewith. When the switch W is seized for operation by the operator at set Z the lamp 15 at U is extinguished, indicating to the supervisor that set Z is busy.

If station V is busy, the switch W, upon testing the busy line, lights lamp 66 to indicate the busy condition of the called station, and causes the busy position locator Y to be started. The busy position locator Y then operates until it finds the switch W. When this occurs, the busy position locator causes the printer at set Z to be operated to print the number of the operator's set in connection with subscriber's station V and causes a lamp at the latter operator's set to be lighted, thus notifying this operator that the connection is not to be released. The calling operator at set Z then releases switch W, which makes switch W selectable by the idle position locator X and extinguishes lamp 15. The calling operator then re-routes the message for transmission by the connected operator. Upon the release of switch W the busy position locator Y is prepared to find any other combination switch that has tested a busy subscriber's line.

It is evident from the foregoing description of the operation that the supervisor at U can ascertain which of the central station operators' sets are busy at any given moment. If the traffic load is such that a portion of the operators' sets can handle it, the supervisor, by operating the keys corresponding to the remaining operators' sets, can make those sets busy and can thereby concentrate the incoming calls on the first-mentioned sets. Likewise, by operating the corresponding key, the supervisor can convert any set into a sending position only.

The description of the various alarms will be deferred until a detailed description of the structure and operation is given.

Referring now to Fig. 1 the subscriber's station V is shown connected to the central station by a line circuit 1. At the subscriber's station, the line circuit 1 extends in series through a low and a high resistance winding of a polar line relay 2, transmitting contacts 4 and printer magnets 3 of the subscriber's printer, and a break key 8 to ground. A printer motor 5, associated with a suitable source of power, serves to drive the printer, and a motor control relay 6 controls the operating circuit of the motor. The polar line relay 2 is designed so that when negative potential is applied to the line circuit 1, the contacts A of the polar line relay are opened, the motor control relay 6 is deenergized, and the printer motor 5 thus stopped, and when positive potential is applied to the line circuit, the contacts A are closed, the motor control relay energized, and the printer motor thereby started, conditioning the printer for the reception or transmission of messages. A calling key 7 is also provided, which serves to shunt the high resistance winding of the line relay 2, thus increasing the line current for a purpose to be explained later.

At the central station, the line circuit 1 extends through a line jack 9, and a marginal line relay 10 to negative battery. A printer may be connected to the line jack 9 to handle overflow calls from subscriber's station V when all of the combination switches, as W, are busy, or to handle all calls from station V providing that station has enough messages to keep a single operator busy. Associated with the line relay is a cut-off relay 11. Similarly, a line and a cut-off relay (not shown) are associated with each of the other subscribers' lines (not shown). The line relays are divided into groups of ten, and associated with each group is a group relay 20.

Associated with the line and group relays is a group of combination finder-connector switches, as W, all of which are associated with the same group of subscribers' stations. These switches are similar, in general, to the combination switch disclosed in a co-pending application Ser. No. 573,323 filed on November 6, 1931 in the name of F. G. Hallden, except that in each switch certain relays have been added, as will be explained later, to control the operation of the busy position locator Y. Each switch, as W, is individual to a particular central station operator's set, as Z, and handles all outward calls from that set and receives inward calls from the subscribers' stations as such calls are distributed to it by the idle position locator X. Each of the switches is provided with the usual private, line and test terminal banks of contacts and with a vertical commutator. Each vertical commutator and the last level of each test terminal bank is provided with an eleventh or home terminal which serves a purpose that will be described later. The terminal contacts in corresponding banks of the switches are multiplied in the usual manner. Thus private contact *p* of switch W is multiplied by conductor 16 to a terminal contact in the private bank, line contact *l* is multiplied by conductor 13 to a terminal contact in the line bank, and test contact *t* is multiplied by conductor 17 to a terminal in the test bank of each of the other combination switches in the same group. Adapted to be moved over the contacts in the private bank of each switch, as W, is a private wiper, as P, adapted to be moved over the contacts in the line bank of each switch, as W, is a line wiper, as L, and adapted to be moved over the contacts in the test bank of each switch, as W, is a test wiper, as T. The three wipers co-operating with the terminal banks of each switch are mounted on a common shaft (not shown). Also adapted to be moved over the terminals, as *r*, in the vertical commutator of each switch, as W, is a wiper R which is mounted on the same shaft as the other three wipers, P, L and T. The shaft carrying the four wipers of each switch, as wipers P, L, T and R of switch W, is adapted to be stepped vertically by a vertical magnet, as 19, and rotated.

by a rotary magnet, as 18, so that the wipers are stepped horizontally. When the shaft is stepped vertically, wiper R moves over the contacts of the vertical commutator while

5 wipers P, L and T are raised to a position adjacent to the first contact of a definite level in their respective banks, and when the shaft rotates, wiper R is raised off the vertical commutator while wipers P, L and T move over

10 the contacts of this level of their respective banks. The remainder of the switch structure will be disclosed later.

When line relay 10, associated with subscriber's station V is operated, it serves to ground the terminal *t* in the test bank of each of the switches, and also serves to energize the associated group relay 20. When cut-off relay 11 is energized, it serves to disconnect the line circuit 1 from the line relay 10 and connect it to terminal *t* in the line bank of switch W and likewise to the terminals multiplied to *t* in the line banks of the other switches. The line and cut-off relays, associated with each of the other subscribers' lines, have similar functions. The group relay 20, when operated, serves to ground the terminal of the vertical commutator in each switch corresponding to the level in which the terminals, associated with the calling subscribers' station, appear, and also to close a start lead 117 extending to the idle position locator X.

As mentioned above, several idle position locators X may, in some instances, be employed: in which case, a group of combination switches is associated with each locator. To provide for an extension of the start lead to a subsequent locator when all of the switches are busy in the group associated 20 with a preceding locator, a chain relay, as 21, is associated with each group of switches. When all of the switches in the associated group are busy, the chain relay, as 21, is released, and upon its release, the start lead 25 which before extended through its front contacts to an idle position locator, as X (Fig. 3), is extended through its back contacts to the next idle position locator.

Each idle position locator, as X, includes 30 a rotary switch X1 and a number of control relays for stepping the wipers of the switch X1 and for controlling the combination switch, as W, selected by the idle position locator.

35 The rotary switch X1 is provided with six contact banks 22-27 with each of which cooperates a double ended wiper, as 28-33 mounted on a common shaft 42. Contacts as 42A, B, C, etc., in the several terminal banks, 22, 23, 24, etc., are associated with switch W. Similarly, in each of these terminal banks there is a contact associated with each one of the other combination switches in the group associated with this idle position locator. The contacts in the several

banks associated with the same switch will be hereafter termed a set of contacts corresponding to that switch.

Of the control relays, a relay 38, when initially operated, serves to energize a relay 39 which causes the closure of an initial circuit for a rotary magnet 40, when subsequently operated serves to stop the vertical stepping of a switch selected by the locator X, and, when next operated, serves to stop the horizontal stepping of that switch. A self-interrupting rotary magnet 40, serves to step the wipers 28-33 as long as the wiper 31 rests on a grounded contact in its associated contact bank 25. As the grounded contacts in this bank are associated with busy combination switches, it is evident that the rotary magnet will step the wipers 28-33 until they rest on a set of contacts associated with the first idle combination switch. A relay 43, which is operated when the wiper 31 reaches an ungrounded contact, serves to disconnect the circuit of the rotary magnet 40 from the wiper 31, and thus prevents the wipers from starting to rotate again when the bank contact, now connected with wiper 31, becomes grounded subsequently, as will be explained later. This relay, upon operating, also serves, as will be explained later, to condition the selected switch for operation. A relay 44', when operated, serves to complete an operating circuit for a relay 45', and this last relay is intermittently energized and released, in a manner to be described later, to close and open alternately a pulsing circuit 80 for the selected switch, thus stepping this switch first vertically to select the level in which the terminals of the calling line appear, and then horizontally until the calling line contacts are found.

When the selected combination switch has found the calling line, the relay 39 is released, and the rotary magnet circuit thus closed through wiper 33. As all but the home contacts in contact bank 27 are grounded, the rotary magnet 40 causes the wipers to step around until wiper 33 rests upon the ungrounded home contact 37 upon which the rotary magnet is de-energized and the wipers brought to rest. 100

The switch W is provided with the usual pulsing relay 44. When the switch is used as a connector, the relay 44 controls the pulsing circuit of the switch, but when the switch is used as a line finder this relay serves merely to energize an associated slow release relay 45, which, in turn, associates the pulsing circuit extending from the associated idle position locator X with the vertical magnet 19. The vertical magnet 19 serves to step the wipers P, L, T and R of the switch vertically, while the rotary magnet 18 serves to step the wipers horizontally in accordance with the vibrations of the pulsing circuit. Off-normal contacts 47 which operate upon the first vertical step taken by the switch, 115 120 125 130

- 6 prepare the pulsing circuit for transfer from the vertical to the rotary magnet when a slow-release relay 46, associated with the vertical magnet, is released. The vertical magnet 19 and the rotary magnet 18 jointly control a relay 45' in the locator X which, in turn, controls the pulsing circuit for operating the vertical magnet 18 and the rotary magnet 19. Consequently, whenever the 10 pulsing circuit of the switch W is closed at the locator X and either the rotary or vertical magnet operated, relay 45' is released opening the pulsing circuit and releasing the vertical or rotary magnet, whichever is 15 operated. The slow-release relay 46 also controls a circuit for operating relay 38 of the locator X, when the wiper R reaches the grounded terminal in the vertical commutator, thus opening the pulsing circuit long 20 enough to release both the vertical magnet 19 and the slow-release relay 46, thereby transferring the pulsing circuit to the rotary magnet 19. When the rotary magnet 19 has caused the wipers to be brought into connection with the terminals of the calling subscriber's lines, the relay 38 in the locator X is operated by the ground on the test contact t, thus opening the pulsing circuit and stopping the wipers on these terminals. A relay 25 51 is provided which is operated when the wipers of the switch W rest on the terminals of an idle subscriber's station. Relay 51, upon operating, serves to connect the subscriber's station, as V, through the switch 30 35 W, to the central station operator's set Z individual with that switch, to open the pulsing circuit of the switch thus preventing any further stepping of the switch, and to restore the idle position locator X to its 40 home position upon which it is in readiness to answer the next incoming call.
- 45 Each switch is also provided with relays 50, 52 and 53. When a switch, as W, is being used as a connector, relay 50 is operated when the wipers of the switch come to rest on the terminals of a busy subscriber's line. Relay 52, which is responsive to the operation of relay 51, serves to complete circuits for notifying the calling central station operator, as Z, that the called subscriber's line is busy, for starting the busy position locator Y, and for preparing a circuit for operating the relay 53 in the switch connected with the busy subscriber's line. When the busy position locator Y finds the switch W, the wipers of which are now in contact with the terminals of the busy line, the busy position locator causes relay 53 of the other switch that is already connected with the busy line 55 to be operated. That relay, upon operating, completes circuits for notifying the operator in connection with the busy line that the connection is not to be released, and for causing the busy position locator to transmit 60 im pulses to the calling operator's printer, which, thereupon, prints the number of the operator's set in connection with the subscriber's station just called.
- 65 At each of the central station operators' sets, as Z, the line circuit normally extends to negative battery through the contacts A of switching relay 55. This relay, controlled either by the key 54 or by relay 43 of the idle position locator X, serves when operated to connect the line circuit through transmitting contacts 56 of the printer and polar line relay 57 to positive battery. The switching relay 55 also controls a guard lamp 58 which is lighted whenever the operator's set Z is busy. A control relay 59, which is normally held energized by alternative circuits completed at the key 54 and at the associated make-busy key 15, serves to control the operating circuit of the printer motor 60. Printer magnets 61 of the set printer are connected in the usual local circuit controlled by the polar line relay 57. A hold relay 62 and a hold lamp 63 are connected in a circuit controlled by the busy position locator Y, while the hold relay, when operated, serves to close a locking circuit for the hold lamp through the contacts of a release key 64. This key likewise controls a locking circuit for the switching relay 55. In addition to the foregoing, a dial 65 for operating switch W and a resistance shunted busy lamp 66, which is lighted whenever a subscriber's line has been tested and found busy, are provided.
- 70 75 80 85 90 95 100 105 110 115 120 125 130
- At the supervisor's position U are located make-busy keys, as 14, associated with each central station operator's set, as Z, and a lamp, as 15, corresponding to each set, as Z. When the make-busy key corresponding to any set is operated, that set is made busy so that the wipers of the idle position locator, as X, pass over the set of contacts of the switch associated with that set, and also the control relay, as 59, at that set is placed under control of the set key, as 54. As previously mentioned, the lamps, as 15, are lighted when the corresponding operator's set is idle, and are extinguished when that set is actually busy, or is "made busy" by the corresponding make-busy key 14.
- 100 105 110 115 120 125 130
- The busy position locator Y (Fig. 4) comprises a rotary switch Y1 and one or more sets of code relays, as Y2. As previously mentioned, it is the function of the busy position locator Y to respond whenever a called subscriber's line is found busy, to set up a local circuit to the calling operator's set and to send over this circuit signals which cause the calling operator's printer to record the set number of the operator in connection with the busy subscriber's line and also to set up another local circuit from the switch in connection with the called subscriber's station to the connected operator's set which operates a hold lamp notifying this operator that the connection is not to be released.

The rotary switch Y1 is provided with three terminal banks 67-69. In the drawings, only contacts 70a, b and c, are shown associated with one of the combination switches, W, but it is to be understood that in actual practice each of the other combination switches would be similarly provided with a set of contacts, as 70a, b and c, in the terminal banks 67-69. Co-operating with the terminal banks 67-69 are double ended wipers 70-72 respectively. These wipers which are mounted on a common shaft 73 are adapted to be rotated step-by-step over their associated terminal banks by a self-interrupting magnet 74 which rotates the common shaft 73.

A relay 75, which is energized when the start lead of the busy position locator Y is grounded at a combination switch, serves to complete an operating circuit for the rotary magnet 74. This magnet operates intermittently so long as wipers 72 rest on a grounded contact in terminal bank 69, thus stepping wipers 70-72 over the contacts on their associated banks. As will be explained later, the grounded contacts in bank 69 are associated with switches that have not tested a busy subscriber's line, while the ungrounded contacts are associated with switches that have tested such lines. A relay 76 is provided which operates and releases relay 75 when wiper 72 reaches the first ungrounded contact in terminal bank 69. A relay 77, responsive to the closure of the start lead and held operated by relay 76, serves to close an operating circuit for a control relay 78, which, upon energizing, connects a suitable source of power to a motor 82. Adapted to be driven by the motor is a shaft (not shown) on which are mounted a plurality of cams (also not shown) each associated with one of the twelve distributor contacts 83-94. The cams are so designed that during every revolution each of the eleven distributor contacts 83 and 85-94 are closed once, contacts 83 being closed first and then the remaining contacts 85-94 being closed in sequential order. Contact 84 is closed several times during each revolution in order to transmit certain code signals, as described later.

Associated with the distributor contacts are two groups of code relays, as Y2. The group Y2 includes six relays 95-100. These relays are adapted to be operated in various combinations, in accordance with circuits completed by the operation of a relay, as 53, in a combination switch connected with a busy subscriber's station. The relays in group Y2 are the tens code relays, and their function is to prepare circuits which are closed at the distributor contacts 85-89 for operating the calling operator's printer to record the tens digit of the number designating the set connected to the busy station. Similarly, a group of units code relays (not shown) are provided, and

their function is to prepare circuits closed by the distributor contacts 90-94 for operating the calling operator's printer to record the units digit of the number designating the set connected to the busy station.

70

With two groups of relays as described, any two digit number from 00 to 99 can be recorded. It is obvious, however, that only a single group of code relays would be needed for single digit numbers, and with three or more groups of relays numbers of any size could be recorded.

75

In order to make certain that the motor 82 will accelerate to operating speed before the local circuit from the busy position locator Y is allowed to control the calling operator's printer, relays 79-81 and 82' are provided, and the conductor 101, which is extended by the operation of relay 76 to the calling operator's printer, is grounded at the contacts A of relay 82', thus making the circuits prepared by the code relays and completed by the closure of the cam controlled distributor contacts ineffective to control the calling operator's printer until the motor 82 has reached operating speed. The motor is designed to reach operating speed by the time the cam controlling the distributor contacts has made one revolution. Relay 79 operates when relay 76 pulls up (if the calling operator's key is in its normal position, as explained later). Relays 80 and 81 are operated, respectively, upon the first subsequent closure and opening of contacts 83 of the distributor contacts, and relay 130 is operated upon the second closure of these contacts, thus removing the shunting ground and placing the calling operator's printer under control of the distributor contacts 84-94. As relay 82' is not operated until the second closure of contacts 83, it is evident that the controlling cam has made at least one complete revolution, and that the motor 82 has therefore reached operating speed.

90

The operation of the above-described system in making an outward and an inward call, respectively, will now be described.

110

Outward call

To make an outward call the key 54 at the central station operator's set Z, which is normally in the center position, is thrown to the left, thereby causing the operation of switching relay 55 and the lighting of guard lamp 58 over obvious circuits. The switching relay 55 locks to ground through the contacts of the release key 64. The operation of the switching relay energizes pulsing relay 44 of combination switch W over a circuit from battery, through low and high resistance windings of relay 44 in series, dial lead 102, lamp 66, dial 65, contacts of switching relay 55 to ground at the release key 64. Relay 44, upon operating, completes an obvious circuit for energizing slow-release relay 45,

115

120

125

130

135

which at its F contacts opens the circuit of the operator's idle lamp 15, thus extinguishing that lamp which indicates to the supervisor at U that operator's set Z is busy. The operation of relay 45, in addition to closing other circuits which will be traced later, at its E contacts grounds contacts 42D in terminal bank 25 of the idle position locator X, thus making the combination switch W busy to incoming calls.

The operator then dials a two digit number corresponding to the location of the bank terminals associated with the subscriber's station V with which a connection is desired. Operation of the dial 65 causes the dial lead circuit 102, which was previously traced through the windings of relay 44, to be alternately opened and closed a predetermined number of times. At each release of relay 44 the vertical magnet 19 is operated to step the switch mechanism and the wipers P, L, T and R one step vertically, while relays 45 and 46, which are slow-releasing, remain energized throughout the series of impulses corresponding to the first dialed digit. The initial circuit for operating relay 46 and vertical magnet 19 may be traced from battery, winding of vertical magnet 19, winding of relay 46, contact B of the off-normal contact 47, eleventh rotary contacts 12, contacts B of relay 45, contacts H of relay 51, to ground on contacts A of relay 44. Upon the first vertical movement of the switch, the off-normal contacts 47 operate, thus transferring the circuit for operating the vertical magnet 19 through contacts B of relay 46 and contacts A of the off-normal contacts, instead of over the previously traced path.

At the end of the first series of dial pulses the switch W has been stepped vertically to the desired level, and when the dial 65 returns to normal the circuit through the windings of relay 44 is closed. Relay 44 comes to rest energized and relay 45 is held operated over a circuit through contacts B of relay 44. After a short interval relay 46 releases, transferring the pulsing circuit from the vertical magnet 19 to the rotary magnet 18. The second series of dial pulses operates relay 44 to energize the rotary magnet 18 intermittently over a circuit which extends from ground through contacts A of relay 44, contacts H of relay 51, contacts B of relay 45, off-normal contacts A, contacts A of relay 46, contacts D of relay 50, and in parallel through winding of slow-release relay 48 and through winding of rotary magnet 18 to battery. Upon the first closure of this circuit relay 48 pulls up, transferring the pulsing circuit through its D contacts and in parallel through the windings of relay 48 and the rotary magnet 18 to battery. The second series of dial pulses causes the switch mechanism and the wipers P, L and T to be stepped in the rotary direction to the proper

bank terminals of the previously selected level. While the switch W is being stepped by the rotary magnet 18, relay 48, being of the slow-release type, remains operated.

When the switch wipers P, L and T come to rest on the selected bank terminals and for a short time thereafter (while relay 48 remains operated), a circuit is extended from the p bank terminal, wiper P, contacts C of relay 48 through the winding of relay 50 and to battery. If the called subscriber's line is idle the circuit from the p bank terminal extends to battery through the winding of cut-off relay 11. In this case relay 50 cannot operate. After a short interval of time relay 48 releases and establishes a circuit from battery through the winding of cut-off relay 11, p bank terminal, wiper P, contacts B of relay 48, lower winding of relay 51, contacts A of relay 50, contacts C of relay 45 to ground. Cut-off relay 11 operates and the lower winding of relay 51 is energized to close only contacts D. Closure of contacts D of relay 51 establishes a circuit from battery through the upper winding and contacts D of relay 51, contacts D of relay 45 and to ground. The additional energy supplied by the upper winding will cause relay 51 to close its remaining contacts.

The following circuit changes are effected by the operation of relay 51. The opening of contacts A opens the circuit of the slow-operating relay 104 (Fig. 2), thus preventing the operation of this relay. As will be explained in detail later, relay 104 controls an alarm for indicating the failure of the combination switch W to complete its operation. The opening of contacts B opens a circuit through chain relay 21. As the operating circuit of relay 21 is multiplied by conductor 105 to similar contacts of an identical relay in other combination switches of the same group, this relay remains operated unless all of the other switches are also busy. The closure of contacts C completes an obvious locking circuit for the cut-off relay 11. The closure of contacts E connects the L wiper through to the operator's set Z over a circuit to be traced later. The closure of contacts F connects relay 53 to the test wiper T. The opening of contacts G opens a connection extending to contacts A of the relay 52. The opening of contacts H opens the pulsing circuit from contacts A of relay 44, thus making any further dial pulses ineffective on the switch W.

The line circuit may now be traced from ground at the subscriber's station through the break key 8, printer magnet 3, keyboard 4, both windings of the polar line relay 2, line 1, line jack contacts 9, contacts A of cut-off relay 11 (now energized), bank terminal Z, and wiper L, contacts E of relay 51, line lead 106 to operator's set Z, contacts B of the switching relay 55, contacts E of the opera-

tor's key 54, to negative battery. It may be noted at this point that, previous to the operation of cut-off relay 11, the line circuit extended to negative battery through the 5 winding of line relay 10. As previously mentioned, the polar line relay 2 at the subscriber's station V is so designed that negative potential will hold its contacts A open, and hence the establishment of a connection from 10 the operator's set Z to the subscriber's station set V has in itself no effect on the station equipment.

After dialling the two digits to select the subscriber's station V, the operator's key 54 15 is restored to the center position. Under this condition the line circuit 106 at the operator's set Z extends from the contacts B of the switching relay 55 through the keyboard contacts 56, contacts C of operator's key 54, winding 20 of polar relay 57, contacts of the operated control relay 59 to positive battery. Upon this reversal of current in the line circuit 1, the polar line relay 2 at the subscriber's station V now operates to close its A contacts, 25 thus establishing a circuit from one pole of a power source through the winding of the motor control relay 6 to the other pole of the power source. The control relay operates to close an obvious circuit through the station 30 printer motor 5 and to close another obvious circuit which shunts out the high resistance winding of the polar line relay 2. Removal of this high resistance winding from the line circuit 1 raises the line current from the idle 35 condition value to a value suitable for telegraphic communication.

A connection is now completed from the operator's set printer at the central office through the finder-connector switch W to the 40 selected subscriber's station printer. The station motor 5 has been started and, as the printer motor 60 at set Z runs continuously, telegraphic communication can now be carried on between the central station operator's 45 set Z and the subscriber's station V.

It should be noted that several provisions are made in the circuit to prevent faulty operation, and particularly to prevent the central station operator from sending a message 50 which, because of some false operation or failure of the lines or equipment, is not received by the called subscriber's printer. If, after dialling, the central station operator should attempt to send without first restoring 55 her key 54 to the center position, she will be warned by the fact that the message is not recorded on her own printer, as under this condition the keyboard 56 is disconnected from the line circuit 106 at contacts C of the 60 key 54. On the other hand, if the key 54 is restored properly, the central station operator's printer set is connected to the line lead 106 which is now closed through the selected subscriber's line 1 to ground at the subscriber's station Y. If the central station opera-

tor should dial a spare line, if the switch should fail to cut through to a working line, if the outside line should be open, if the polar line relay 2 at the subscriber's station V should fail to function, if failure of the local power supply at station V, or other cause, should prevent the operation of control relay 6 and the high resistance winding of the polar line relay 2 should thus remain in the line circuit 1, the latter circuit is left open or the line current is so reduced that the operator's printer at Z acts as though connected to an open line and no record of the message will be made by that printer. This serves as an indication to the central station operator that connection has not been established with the called subscriber's printer.

After the message has been transmitted, the central office operator may release the connection by operating the release key 64. The 85 operation of this key opens the circuit of the guard lamp 58 and removes locking ground from the winding of the switching relay 55 so that this relay releases, thus applying negative battery to the line lead 106, operating the polar line relay 2 at the station V and restoring the station circuits to normal. Ground is also removed from the dial lead 102 extending to the windings of relay 44, so that this relay releases. The release of relay 44 90 opens the circuit of relay 45 which releases. The release of relay 45 opens the circuit through the upper winding of relay 51, whereupon this relay releases to restore to normal the circuits previously traced through its contacts. The release of relays 45 and 51 95 establishes a circuit from the ground on contacts A of relay 44, contacts H of relay 51, contacts A of relay 45, off-normal contacts C, winding of release magnet 49, winding of relay 107 (Fig. 2) to battery. The release magnet 49 thereupon operates over the circuit traced, restoring the switch mechanism to normal, at which time the off-normal contacts 47 open to de-energize the release magnet 49. Release of relay 45 also removes ground from the bank terminal 42D of the idle position selector switch X and connects this ground to the operator's idle lamp 15 individual to switch W. The switch W is now in condition to receive inward calls and the operator's idle lamp 15 is lighted to inform the supervisor that the position is idle.

If, because of some mechanical defect, the 120 release function of the switch W is not completed, the circuit through the release magnet 49 and the winding of relay 107 (Fig. 2) is maintained through contacts C of the off-normal springs 47. Relay 107 is then held operated to maintain an obvious circuit through the winding of a dash-pot relay 108. After a predetermined interval dash-pot relay 108 operates, causing a green lamp 109 to light and bell 110 to ring. The attendant 125 is thus informed by the bell that a switch is 130

in trouble, while lamp 109 indicates the row or shelf on which the defective switch is located. It should be noted also that, while such a switch is stuck and until it is completely released, ground from off-normal contacts D is maintained on bank contact, as 42D, in bank 25 of the idle position locator X, to prevent this switch from being selected for an inward call while it is in trouble.

10 In case the called subscriber's station V is busy, the p bank terminal will be grounded through contacts C of relay 51 in the finder-connector switch in connection with that station. Hence, when, before the release of relay 48, the switch wipers P, L and T come to rest on the bank terminals associated with station V, a circuit is closed from ground at the p bank terminal through the P wiper, contacts C of relay 48, winding of relay 50 to battery. Relay 50 then operates and remains locked over a circuit which extends from battery through the winding of relay 50, make-before-break contacts E of relay 48, contacts B of relay 50, contacts C of relay 45 to ground. Under these conditions, a circuit is closed for operating relay 52 which may be traced from ground through contacts C of relay 50, contacts A of relay 48, winding of relay 52 to battery. Relay 52 then 50 operates, closing at its D contacts a circuit which shunts the high resistance winding of relay 44, thus increasing the current in the dial lead circuit 102 and thereby lighting the busy lamp 66 at operator's position Z.

35 The circuit changes effected by the operation of relay 52, other than the shunting of the upper winding of relay 44, are effective in controlling the operation of the busy position locator Y, which operation will now be described. As previously mentioned, it is the function of the busy position locator Y to respond whenever a called line is found busy, to set up a local circuit to the calling operator's set, and to send over this circuit signals which cause the operator's printer to record the position number of the operator who is connected to the busy line. At the same time a lamp, as 63 (Fig. 2), is lighted at the central station operator's set in connection with the busy line, thereby indicating to this operator that the connection is not to be released since a message is to be rerouted for transmission to the connected subscriber's station.

53 Only the switch W is shown in the drawings. As previously mentioned, however, the banks of other switches in the same group with W are multiplied thereto by conductors 13, 16 and 17. In the switch in connection with the busy subscriber's station, the relay, as 53, is connected through contacts F of relay 51 of that switch, wiper T, contacts t, conductor 17, contact t and wiper T of switch W, contacts G of relay 51 (which is unoperated) to contacts A of relay 52.

When relay 52 of switch W operates, the busy lamp at set Z is lighted over a circuit that may be traced from battery, low resistance winding of pulsing relay 44 (the high resistance winding being shunted), contacts D of relay 52, dial lead 102, busy lamp 66, dial 65, contacts of switching relay 55 to ground at release key 64; and ground is removed from the corresponding bank terminal 70C of the busy position locator switch Y 75 while ground is connected to the start-lead 111 which is multiplied to the relays, as 52, in all of the combination switches in the same group. Ground on the start-lead completes a circuit through the winding of relays 77 and 75. This circuit may be traced from battery, winding of relay 77, contacts E of relay 76, winding of relay 75, start-lead 111 to ground on contacts E of relay 52 of switch W. Relay 77 operates, closing an obvious circuit for control relay 78 which, in turn, pulls up, starting the motor 82 which drives the cam for controlling the distributor contacts 83-94. Relay 75 operates and establishes a circuit from battery through the switch stepping magnet 74, contacts of this magnet, contacts of relay 75, thence over two parallel circuits as follows: (1) winding of relay 76 to ground, and (2) wiper 72 and a terminal in terminal bank 69 which may or may not be grounded. The resistance of relay 76 is of such a value that the stepping magnet 74 will not operate in series with it. If the switch wipers 70-72 are resting on bank terminals corresponding to a finder-connector switch that is either idle or connected through to a station line in the normal working condition, a circuit is extended from ground through the contacts F of a relay, as 52, in this switch, through a contact in terminal bank 69 and wiper 72 to the busy position locator stepping magnet 74. The stepping magnet then operates, breaking its own circuit and releasing, thus advancing the rotary switch Y1 one step. If the wiper now finds ground on the next contact in bank terminal 69, the stepping magnet circuit will again be closed, causing the rotary switch Y1 to advance one more step. This action continues and the switch steps around until the wiper 72 reaches an ungrounded contact, as 70C, in terminal bank 69. This ungrounded contact corresponds to the finder-connector switch W in which the relay 52 is operated. It should be noted, however, that if two central station operators dial busy lines at about the same time, a relay, as 52, will be operated in two combination switches and the rotary switch Y1 will stop when the wiper 72 reaches the contacts in terminal bank 69 connected to the first of these two switches. In this case, one of the two operators will not receive the busy position locator signal immediately, but must 120 125 130

wait until the other operator releases the circuit.

As soon as the wiper 72 associated with bank 69 reaches terminal 70C which is not grounded, relay 76 operates since its winding is no longer shunted, while stepping magnet 74 fails to operate. Operation of relay 76 opens at its E contacts the circuit to the winding of relay 75 and to the winding of relay 77. 5 Relay 75 now releases, opening the circuit of stepping magnet 74, but relay 77, being slow-releasing, remains energized until relay 76 at its C contacts closes a locking circuit for itself which extends to battery through another 10 winding of relay 77. Relay 76 at its D contacts also connects battery through a winding of relay 77 to the wiper 71 associated with terminal bank 68 and thence through contacts 70B, contacts B of relay 52, contacts G of 15 relay 51 in switch W, T wiper and bank terminal t, thence over conductor 17 to the t bank terminals of all other finder-connector switches. The relay corresponding to relay 51 of switch W in the "busy" switch, which 20 is in connection with the called line, is operated, so that the circuit just traced extends through the t bank terminal and wiper T of this "busy" switch, contacts F of the relay corresponding to relay 51, winding of relay 25 53 to ground. Relay 53 of the "busy" switch then operates.

Operation of this relay extends ground over three circuits as follows:

(1) Contacts C of relay 53, winding of the 35 hold relay at the connected operator's set, corresponding to relay 62 of the set Z, and to battery;
 (2) Contacts B of relay 53 to a terminal, as 136, of the units code relay group;
 40 (3) Contacts A of relay 53 to a terminal, as 136, of the tens code relay group.

The termination of circuits (2) and (3) is such that relays of the tens code group Y2 and of the units code group (not shown) 45 are operated to set up five-unit signal combinations corresponding to the tens digit and the units digit, by which this "busy" finder-connector switch and its associated operator's position are designated. The circuit traced to the hold relay, corresponding to relay 62, of the "busy" operator's set causes this relay to operate and lock itself to ground through the release key corresponding to key 50 64. This circuit also extends through the hold lamp corresponding to lamp 63 at this position and to battery. The hold lamp lights, informing the "busy" operator that the connection is to be held for an additional 55 outgoing message.

60 As previously mentioned, the motor 82 was started when the relay 78 was operated. When the wiper 70 comes to rest on contact 70a, which is in connection with switch W, a circuit is completed for operating polar relay 79 which may be traced from positive

battery, winding of polar relay 57 (Fig. 2), contacts C of key 54 (which was restored when the operator noticed the lighted busy lamp), transmitter contacts 56, contacts B of switching relay 55, conductor 106, contacts C of relay 52 (Fig. 1), contacts 70A (Fig. 4), wiper 70, contacts B of relay 76, winding of relay 79, conductor 101, to ground on contacts A of relay 82'. Relay 79, therefore, operates, 75 preparing a circuit for relay 80. Upon the first closure of contacts 83 of the distributor by the cam (not shown) relay 80 is operated over a circuit from battery, winding of relay 80, contacts B of relay 81, contacts of 80 polar relay 79, to ground on contacts 83. Relay 80 locks through its locking contacts, winding of relay 81 to ground on contacts A of relay 76. When cam operated contacts 83 open, removing the short circuit from across its winding, relay 81 operates. The operation of relay 81 prepares an operating circuit for relay 82'. Upon the second closure and opening of distributor contacts 83, relay 82' operates over a circuit from battery, winding of relay 82', contacts A of relay 81, contacts of polar relay 79, to ground on contacts A of relay 76. The cams controlling the distributor contacts 83-94 have, therefore, made at least one complete revolution and the motor 82 is now running at operating speed. The operation of relay 82' 90 opens at its A contacts the shunt around the circuits controlled jointly by the code relays and the distributor contacts, so that the operator's printer at set Z is now under control of these circuits.

As the cams (not shown) driven by the motor 82 revolve, contact 83 closes momentarily once per revolution, but as relay 82' is locked, 105 the contacts 83 have no effect. The remaining contacts 84-94 of the distributor close in a sequence such that, during one revolution, a figure shift signal, a dash signal, and a two digit number which corresponds to the 110 code relay set-up, are sent out over the line 101.

The cam which controls the figure shift contacts 84 is so cut that these contacts will transmit, first, a figure shift signal and a dash signal, and then, during the remainder of the revolution, will close to provide two stop pulses, one for the tens digit signal and the other for the units digit signal. The five pulses of the tens signal are controlled 115 by successive closures of the contacts 85-89, and the character of these pulses (whether marking or spacing) is controlled by the contacts of the tens code relays 95-100 inclusive. The five pulses of the units signal are controlled by successive closures of the contacts 90-94, while the character of these pulses is controlled by the contacts of the six units code relays (not shown), which are arranged similarly to the six tens code relays 95-100. 120

As the cams (not shown) revolve a series

of impulses will be sent over the line which will cause the "calling" operator's set printer to shift to the figure position and to print a dash followed by a two digit number which 5 will correspond to the code combinations set up on the tens and units code relay groups. Since the setting of these code relay groups has been controlled by the relay corresponding to relay 53 in the "busy" switch in connection with the called line, and since this switch is individual to a particular operator's position, the number which the distributor sends back to the calling operator will indicate the position number of the operator in connection with the called subscriber's station. It is to be noted that the units group of code relays co-operate with distributor contacts 90-94 to send the units digit signals over conductor 140 and thence over conductor 101 to the operator's printer at set Z. The calling operator at Z notes this number on the message blank and then operates the release key 64.

The operation of the release key restores 25 to normal, in the manner previously described, the circuits and mechanism of the combination switch W. When the switching relay 55 releases upon the operation of the release key, negative battery is applied 30 through contact A of relay 55 (Fig. 2) to the previously traced circuit of the polar relay 79, with the result that the contact of that relay is opened. Relay 50 releases when its circuit is opened at contact C of relay 45, 35 and relay 50 in turn opens the circuit of relay 52 at contact C of relay 50. When relay 52 releases it opens at its B contacts one winding of relay 77; at its C contacts the section of the line circuit between 106 and 101; at its D contacts the shunt around the high resistance winding of relay 44; at its E contacts the start-lead 111 for the busy position locator; and at its F contacts, connects ground to contact 70c in terminal bank 69, thereby causing relay 76 to release since both 40 terminals of its winding are grounded. Upon releasing, relay 76 at its contacts A opens the locking circuits of relays 80 and 82' and the operating circuit of relay 81; at its C contacts opens the other winding of relay 77 which releases after an interval; and at its E contacts reconnects relays 77 and 75 to the start-lead 111. The release of relay 77 and the consequent release of relay 78 re-opens 45 the operating circuit of motor 82, stopping the rotation of the cams (not shown). It is to be noted that the relay 77 is a slow-release relay. This is to prevent the motor 82 from stopping before the busy position locator has time to respond to another "busy" call, if such a call should be waiting. The release of relay 82' reconnects ground, at its A contacts, to conductor 101, and the release 50 of the other relays mentioned prepares the busy position locator to answer the next

switch that has called a busy line. It is to be noted that the wipers of the busy position locator do not return to a normal or home position when the busy position locator is released, but remain on the contacts where 70 they were last placed.

The operation of the code relay groups in setting up circuits to the distributor contacts of the busy position locator is illustrated by 75 the following chart. The first column of this chart gives the number to be sent to the calling operator's printer. This number corresponds to the terminal connection of the leads from contact A of the relay in the "busy" switch corresponding to relay 53 in switch W. The second column gives the code relay terminal grounded by relay 53 of switch W. The third column shows the tens code relays 80 that are operated, and the fourth column shows the circuits set up to the distributor 85 contacts which correspond to the five unit printer code signal of the number to be sent.

Tens digits to be sent	Terminals grounded by relay 53 of switch W	Code relays operated	Distributor contact connections closed	90
1	130	(1) 95, 96, 100	(1) 85, 86, 87, 89	
2	136	(2) 98, 100, 95	(2) 85, 86, 89	
3	131	(3) 95	(3) 85	
4	138	(4) 99, 98	(4) 85, 88	
5	139	(5) 100	(5) 89	
6	135	(6) 97, 100, 95	(6) 85, 87, 89	95
7	133	(7) 96, 95	(7) 85, 86, 87	
8	134	(8) 97, 98	(8) 86, 87	
9	137	(9) 99, 100	(9) 88, 89	
0	132	(0) 96, 100	(0) 86, 87, 89	

Similarly, to send corresponding units digits, similarly related units code relays 100 would be operated, similarly related terminals, as 136' would be grounded by relay 53 of switch W, and similarly related distributor contacts in the group 90-94 inclusive 105 would be grounded; and circuits thus prepared to operate the calling operator's printer to print the units number.

Alternative arrangement for lamp bank indication 110

In Fig. 5 is shown an alternative arrangement whereby a visual indication, rather than a printed record, of the number of the 115 busy operator's position is given by means of a bank of signal lamps. These signal lamps comprise a tens bank 146 and a units bank 147. A pair of lamps, one 148 in bank 146 and another 149 in bank 147, is controlled by relay 53 in switch W. Similarly, the relays corresponding to relay 53 in each of the other switches control a pair of lamps, one in bank 146 and the other in bank 147. Upon the operation of relay 53 in switch W, 120 lamps 148 and 149 are lighted, indicating to the operator who has called a subscriber's line in connection with set Z that the latter set is connected with the busy line. Similarly whenever an operator calls a line in connection 125 with one of the other switches, the relay 130

- corresponding to relay 53 in that switch is operated, and a pair of lamps, as 150 and 151, are thereby lighted, indicating to the calling operator that the set associated with the busy switch is in connection with the called line. It is to be noted that the lamp bank is common to the operators' sets, and is so positioned that it is visible to any of the operators at these sets.
- 10 In addition, a multiple connection to the hold relay and hold lamp at each operator's set, as Z, is placed under control of either relay 52 or 53 in the associated combination switch W. Consequently, the hold lamps 63 at both the calling and the busy operators' sets are lighted. This arrangement is necessary to take care of the situation when more than one central station operator has called a busy subscriber's line. As previously explained, the busy position locator is then associated with the calling switches one after another, and as a result different numbers, corresponding to the different "busy" sets are flashed on the lamp bank. Consequently, means must be provided to enable a calling operator to distinguish from the numbers flashed, the number designating the busy set connected to the subscriber's line that he has called.
- 20 In the drawings, the relays 52 and 53 are shown connected for operating the busy position locator Y and the lamp banks 146 and 147. The manner in which these relays are connected with the circuits of the switch W is indicated in the description to follow and may be traced by reference to Fig. 1. It is to be noted that in Fig. 5, parts similar to those in Fig. 1 are designated by the same reference characters.
- 30 Assume that an operator, such as Z, has dialled a busy line, as 1. Under these conditions relay 52 of switch W operates over a circuit from battery, winding of relay 52, conductor 116, contacts A of relay 48 (see Fig. 1), to ground at contacts C of relay 50. Upon operating, relay 52 at its A contact opens the connection from contact 42A in bank 22 of locator X over conductor 144, contact A of relay 52, conductor 115 to the test wiper T of switch W; at its B contact connects the test wiper T of switch W to contact 70B in bank 68; at its C contact connects conductor 143, which extends in series through the hold relay 62 and the lamp 63 at operator's set Z, to contact 70a in bank 67; at its D contacts completes a shunt circuit over conductors 102 and 142 around the high resistance winding of pulsing relay 44 in switch W, thereby lighting the busy lamp 66 at set Z in a manner previously described; at its E contact grounds the start-lead 111, which is multiplied by conductor 145 to other relays, as 52, in the other switches; and at F removes ground from contact 70c

corresponding to switch W in bank 69 of the busy position locator Y.

Ground on the start-lead operates relay 75 over an obvious circuit. Operation of relay 75 establishes a circuit from battery through the winding and contacts of the rotary magnet 74, contacts of relay 75, thence over two parallel circuits, one extending to the wiper 72 associated with terminal bank 69 and the other extending to ground through the winding of relay 76. If the busy position locator switch is not resting on terminals associated with a switch that has tested a busy subscriber's line, the circuit traced to the wiper 72 associated with terminal bank 69 extends to ground through the terminal contact. Under these conditions relay 76 is short-circuited and does not operate, but the rotary magnet 74 does, thereafter opening its own circuit and releasing, to advance the wipers 70-72 of the switch one step.

This action will continue until the wipers of the busy position locator switch reach the bank terminals associated with the calling finder-connector switch W. At this time, as previously explained, the rotary magnet 74 and the relay 76 are connected in series, but only relay 76 operates, locking through its own contacts. The wipers of the switch, therefore, remain in contact with terminals associated with the switch W. Operation of relay 76 opens the circuit through the winding of relay 75, allowing this relay to release and open the circuit of the rotary magnet 74. Relay 76 also connects battery to a circuit extending through the wiper 71 associated with bank terminal 68 of the busy position locator Y, contacts B of relay 52, conductor 115, contacts G of relay 51 (see Fig. 1) of the calling switch W, T wiper and t bank terminal of this switch, thence over the multiplied bank wiring, t bank terminal and T wiper of the busy switch, contacts F of relay in this switch corresponding to relay 51 in switch W, conductor 114, winding of the relay, which corresponds to relay 53 in switch W, to ground. The relay in this busy switch, corresponding to relay 53 of switch W, operates over this circuit.

Operation of relay 76 also establishes a circuit from ground through contacts A of relay 76, wiper 70 associated with bank terminal 67 of the busy position locator switch, contacts C of relay 52 of the calling finder-connector switch W, conductor 143, and in parallel through the winding of hold relay 62 and through the hold lamp 63 (see Fig. 2) of the calling operator's set Z. The hold relay locks to ground through the release key 64, and the hold lamp 63 lights to inform the operator to watch the lamp bank indicator for the number of the "busy" operator's position which is in connection with the called line.

It is to be noted that contact C of the relay

53 and the armature associated with contact C of relay 52 in each combination switch are multiplied to conductor 143, which is connected in multiple through the hold relay 62 and the holding lamp 63 at the associated operators' sets. Consequently, when the switch W is a "calling" switch and relay 52 is operated, the lighting of the holding lamp informs the calling operator to watch the lamp bank, and when the switch W is a "busy" switch and relay 53 is operated, the lighting of the holding lamp informs the "busy" operator that the connection is to be held until a re-routed message for the connected subscriber is received.

At the time of the operation of the relay of the "busy" finder-connector switch, corresponding to relay 53 of switch W, three circuits were closed as follows:

20 (1) From ground through contacts C of the relay corresponding to relay 53 and in parallel through the winding of the hold relay 62 and through the hold lamp 63 of the operator's set which is in connection with the called lines;

(2) From ground through contacts B of this relay to a lamp 148 in the tens row 146, which corresponds to the tens digit by which this operator's set is identified;

30 (3) From ground through contacts A of this relay to a lamp 149 in the units row 147, which corresponds to the units digit of the number by which this operator's set is identified.

35 Operation of the hold lamp 63 just described will inform the operator in connection with the busy subscriber's line that another message is to be sent and that the station is not to be released. The two lamps 148 and 149 of the lamp bank unit light to indicate to the calling operator the number of the position which is in connection with the called line. The operator, upon noting this number, re-routes the message accordingly.

40 The calling operator then operates the release key 64 (Fig. 1) to restore the calling finder-connector switch W to normal. Relay 52 of this switch releases, transferring ground from the start-lead 111 to the corresponding bank terminal 70c of the busy position locator switch. This ground will extend through the wiper 72 associated with terminal bank 69 to shunt the winding of relay 76. Relay 76 thereupon releases, re-

55 toring, in the manner previously described, the circuits of the busy position locator Y to normal. If another busy call is waiting, relay 75 operates immediately and the busy position locator Y responds to this call, but if there are no busy calls waiting, the wipers of the busy position locator switch remain on the bank terminals last used.

60 It should be noted that the number displayed by the lamp indicators 146 and 147 at any time will be the number of the po-

sition in connection with the "busy" line which is wanted by the calling operator. This lamp bank may be common to a fairly large group of operators, several of whom may dial busy lines at the same time. To avoid confusion of busy position numbers during busy periods, the calling operator, after noting the lighted busy lamp 66, should watch the hold lamp which lights at the calling position as well as at the busy position, as previously explained. When the hold lamp lights, the calling operator should refer to the lamp bank indicator. The number displayed on the lamp bank indicator at this time will be the number of the position which is in connection with the called line.

Inward service

To establish a connection from the subscriber's station set V to a central office operator, such as Z, the calling key 7 (Fig. 1) at the station V is operated. This action shunts out the high resistance winding of the polar line relay 2 at station V, and increases the line current from the idle condition value to a value sufficient to operate marginal line relay 10. Contact A of line relay 10 is wired to all *t* bank terminals corresponding to this station number, while contact B of this relay is wired to the winding of a group relay 20 which is associated with the particular switch level in which the calling line is located. The operation of line relay 10 will thus cause the proper *t* bank terminal in all of the switches, such as W, to be grounded and the proper group relay, such as relay 20, to be operated. Operation of group relay 20 connects ground to a terminal *r* of the vertical commutator corresponding to the level in which the terminal contacts of the calling line appear. Group relay 20 also connects ground to contacts of chain relay 21 to control the starting of the idle position selector.

As previously stated, it is preferable in large installations to provide more than one idle position selector in order to avoid excessive wear on the wipers of the selector, which might occur if a single switch had to rotate over the terminals associated with a large number of operators' sets. In such an installation it is possible that all of the operators' sets associated with one idle position selector might be busy at the same time. In this case it would be necessary to handle the next incoming call through the second idle position selector and a second group of operators' sets. One chain relay, as 21, is associated with the group of switches that are served by one idle position selector. The winding of this relay 21 is multiplied to normally grounded contacts B of relay 51 in switch W and to a similar contact of the corresponding relay in each of the other switches in this particular group. A chain relay, as 21, is similarly associated with each addi-

tional group of switches and each additional idle position locator. It is obvious that, as long as one or more switches of a group, as switch W, are idle, the associated chain relay, as 21, will be operated, but that, as soon as all switches of this group are busy, the chain relay, as 21, will release. Release of the chain relay, as 21, switches the start-lead circuit 117 to the next idle position selector 10 (not shown) so that one of the operators' sets of the second group will receive the next incoming call.

Assuming that some of the switches associated with the first idle position selector X 15 are idle, the corresponding chain relay 21 will be operated as shown, and the start-lead 117 will be extended through the winding of relay 129, contacts B of chain relay 21, to the idle position locator X and thence through 20 contacts A of relay 44', winding of relay 45', wiper 28 associated with terminal bank 22 of the rotary switch X1, home contact 34, winding of relay 38 to battery. Relays 129, 45' 25 and 38 operate over the circuit just traced. The closure of contacts C of relay 38 connects the winding of this relay directly 30 through contacts A of relay 44' to the start-lead 117, so that relay 38 is held operated independently of the wiper 28 associated with terminal bank 22. This action also short 35 circuits the winding of relay 45', which releases, its operation serving no useful purpose at this time. The closure of contacts B of relay 38 establishes a circuit from ground 40 through the lower or low resistance winding of relay 39, contacts B of relay 38, upper or high resistance winding of relay 39, to battery. Relay 39 operates, establishing a circuit through winding of the rotary magnet 40 and rotary magnet contacts 118, contacts A of relay 39, thence in parallel through the winding of relay 43 to ground, and through contacts B of relay 43, wiper 31, to grounded home contact 36. The rotary 45 magnet 40 now operates, opening its own contacts 118 and releasing to step the switch X1 one step. The wiper 31 associated with terminal bank 25 comes in contact with the bank terminal which is associated with the number one finder-connector switch of this group. If this switch is busy its relay corresponding to relay 45 of switch W is operated, extending ground to this bank terminal, and the stepping magnet 40 accordingly again 50 operates and releases to step the idle position locator switch X1 one more step. The idle position locator switch X1 steps around in this manner until the wiper associated with terminal bank 25 comes in contact with an ungrounded bank terminal, i. e., one corresponding to an idle finder-connector switch. When this occurs the circuit through the rotary magnet 40 extends to ground through the winding of relay 43. 55 The relay 43 operates but, because of the

circuit resistance, the rotary magnet 40 does not receive enough current to operate, and, therefore, the wipers 28-33 come to rest on terminals associated with the lowest numbered finder-connector switch that is idle. It will be assumed that this is switch W.

Operation of relay 43 connects ground through its A contacts, wiper 30 associated with terminal bank 24, terminal contact 42C, windings of relay 44 of switch W in series and to battery. This ground also closes a circuit extending over the dial lead 102 and through the busy lamp 66 and switching relay 55 of the associated operator's set Z to battery. The switching relay 55 thereupon operates, locking up through the release key 64, thus closing a circuit for lighting the guard lamp 58 and applying an additional ground to the dial lead 102. Relay 44 operates, closing an obvious circuit through the winding of relay 45. Relay 45 thereupon operates, closing a circuit from ground through its contacts E, bank terminal 42D and associated wiper 31 of the idle position locator switch X1, contacts C of relay 43, winding of relay 44' to battery. Relay 44' operates, establishing a circuit from battery through the winding of relay 45', contacts C of relay 44', wiper 29 associated with terminal bank 23, bank terminal 42B of the idle 95 position selector switch X1, in series through so-called "interrupter" contacts associated with the vertical magnet 19 and rotary magnet 18 of the selected finder-connector switch W and to ground. Relay 45' operates over the circuit just traced. At the time that relay 44' operated, relay 38 was released by the opening of contacts A of relay 44', so that a circuit may now be traced from ground through the lower or low resistance winding of relay 39, contacts A of relay 38, contacts of relay 45', contacts D of relay 43, wiper 32 associated with terminal bank 26, contacts H of relay 51, contacts B of relay 45, eleventh rotary contacts 12, off-normal contacts B, winding of relay 46, winding of vertical magnet 19 and to battery. The vertical magnet 19, relay 46 and relay 39 operate over the circuit traced.

The operation of the vertical magnet 19 opens at the interrupter contacts mentioned above the circuit of relay 45' which, therefore, releases, opening the circuit through relays 39 and 46 and the vertical magnet 19. Both relays 39 and 46 are slow-release relays and do not release at this time, but the vertical magnet 19 does release, reclosing the interrupter contacts, and thereby re-energizing the relay 45'. The relay 45', upon re-energizing, closes the previously traced circuit for the vertical magnet 19. When the vertical magnet was operated it caused the switch W to take one vertical step, thereby operating the off-normal contacts 47. When the relay 46 operates a circuit is prepared

for subsequently operating relay 38. This circuit may be traced from battery, winding of relay 38, contacts B of relay 44', winding of relay 45', wiper 28, contact 42A, contacts C of relay 46 to the wiper R co-operating with the vertical commutator. The off-normal contacts and relay 46 are now operated so that the pulsing circuit to the vertical magnet 19 extends through the off-normal contacts A through contacts B of relay 46, winding of relay 46, winding of vertical magnet 19 to battery.

As stated above, the operating circuit for the vertical magnet is again closed, and upon the energization of the vertical magnet the interrupter contacts are again opened, releasing relay 45' and re-opening the vertical magnet circuit. This reciprocal action between the vertical magnet 19 and the relay 45' of the idle position selector X causes the vertical magnet circuit to be alternately opened and closed, thus stepping the finder-connector switch W vertically. As the switch steps vertically the vertical wiper R is carried over the terminals, as r, of the vertical commutator, and when the switch reaches the level in which the calling line is located, a circuit will be extended from the ground through contacts B of group relay 20, segment r of the vertical commutator, associated wiper R, contacts C of relay 46, contact 42A of terminal bank 22 and associated wiper 28 of the idle position selector switch X1, winding of relay 45', contacts B of relay 44', winding of relay 38 to battery. Relay 45' is held energized to prevent any further vertical stepping of the switch. Relay 38 operates and at its A contacts opens the ground circuit to the relay 46 and the vertical magnet 19. The relay 38 at its B contacts closes a local holding circuit through the windings of relay 39.

The finder-connector switch W consequently comes to rest with its wipers advanced to the level of the bank terminals of the calling line, and after a short interval of time relay 46 releases. Release of this relay opens the circuit from the vertical wiper R associated with the vertical commutator to the winding of relay 38, thus releasing relay 38. Release of relay 38 establishes a pulsing circuit through the lower or low resistance winding of relay 39, contacts A of relay 38, contacts of relay 45', contacts D of relay 43, wiper 32 and terminal bank 26, contacts H of relay 51, contacts B of relay 45, eleventh rotary contacts 12, operated off-normal contacts A, contacts A of relay 46, contacts D of relay 50 and in parallel through the rotary magnet 18 and the winding of slow-release relay 48 to battery. The rotary magnet 18 thereupon operates causing the switch shaft and wipers to take one rotary step and opening the rotary interrupter contacts. The circuit to the winding of relay 45', which was closed upon

the release of the vertical magnet 19, is now open at the rotary magnet contacts and this relay releases opening the circuit to the rotary magnet 18 and relay 48 of the finder-connector switch W. The rotary magnet 18 then releases closing its contacts, but since relay 48 of the finder-connector switch W is of the slow-release type it remains operated. Closure of the rotary magnet contacts again establishes a circuit through the winding of relay 45' and this relay again operates to energize the rotary magnet 18 and the relay 48 of the finder-connector switch.

This action continues until the wipers of the finder-connector switch W are stepped around to the bank terminals associated with the calling line. When these bank terminals are reached, a circuit is closed from ground through contacts A of line relay 10, t bank terminal and wiper T, contacts G of relay 51, contacts A of relay 52, bank terminal contact 42A, wiper 28 of the idle position selector switch X1, winding of relay 45', contacts B of relay 44', winding of relay 38 to battery. Relay 38 then operates opening the circuit previously traced through its A contacts to the windings of the rotary magnet 18 and relay 48 so that the finder-connector switch W comes to rest on the bank terminals of the calling line 1.

After a short interval relay 48 of the finder-connector switch releases closing a circuit from battery through the winding of cut-off relay 11, p bank terminal, wiper P, contacts B of relay 48, lower winding of relay 51, contacts A of relay 50, contacts C of relay 45 to ground. Cut-off relay 11 then operates while relay 51 also operates but closes at first only its D contacts. Closure of the D contacts of relay 51 energizes the upper or high resistance winding, thus operating the remaining contacts of relay 51.

The following circuit changes are effected by the operation of relay 51:

(1) The opening of its A contacts opens a circuit which has extended from ground on contacts D of relay 45 through contacts A of relay 51, winding of dash-pot relay 104 to battery;

(2) The opening of its B contacts opens a circuit from ground through the winding of the chain relay 21;

(3) The closure of its C contacts connects ground to the P wiper and thence through the winding of cut-off relay 11 to hold that relay operated and to make the line 1 busy to other calls;

(4) The closure of its D contacts closes a circuit through the high resistance winding of relay 51, as previously described;

(5) The closure of its E contacts connects the line circuit from the L wiper over the "line lead" 106 through contacts B of the switching relay 55 at the operator's set Z, thence through the keyboard contacts 56, con-

tacts C of the operator's key 54, winding of the polar relay 57, contacts of the control relay 59 to positive battery;

(6) The closure of its F contacts extends a connection from the T wiper to the winding of relay 53 to ground;

(7) The opening of its G contacts opens the circuit previously traced to the winding of relay 38 of the idle position selector X;

(8) The opening of its H contacts opens the circuit to the rotary magnet 18 and relay 48 of the finder-connector switch W.

At the time that cut-off relay 11 operated, the circuit through the winding of line relay 10 was opened and this relay released to open the circuit of group relay 20. Release of line relay 10 removes ground from the t bank terminal and release of group relay 20 removes ground from the corresponding level r of the vertical commutator and from the start-lead 117.

The circuit through the winding of relay 38 being now open, this relay releases opening the circuit of the upper or high resistance winding of relay 39. The lower or low resistance winding of relay 39 is now re-connected into the pulsing circuit through contacts A of relay 38, but as this circuit is now open at contacts H of relay 51, relay 39 releases. Release of relay 39 opens the circuit through the winding of relay 43 so that this relay releases and, in turn, releases relay 44'. Release of relay 44' also establishes a circuit from battery through the winding of the idle position selector stepping magnet 40, contacts 118 of this magnet, contacts B of relay 39, contacts D of relay 44', wiper 33 to ground through the contact of terminal bank 27. All of the terminals in this bank except that corresponding to the home position of the switch are grounded, as previously mentioned, so that the rotary magnet 40, through the action of a self-interrupting circuit, will step the idle position selector switch X1 to the home position, at which position the stepping circuit will be opened at ungrounded home contacts 37. The idle position selector switch and the relays associated with it are now restored to normal and the idle position selector X is in condition to respond to another incoming call.

It should be noted that the rotary switch of the idle position selector always returns to its home position after handling an inward call. Therefore, it always starts from the home position, and each inward call is always distributed to the lowest numbered operator's position that is idle. This concentrates the traffic load on the operators' positions, so that, as the traffic received during the day varies, the number of operators required to handle it can be easily determined. The idle operator lamps, such as 15, are also useful for this purpose. The idle position locator is, however, designed to start only from its

"home" position. If one or more additional calls should be received while a switch is hunting for the first call, the start lead 117 extending from contacts A of a group relay, such as 20, through contacts B of relay 21 to contacts A of relay 44' will remain grounded. When relay 44' releases, the circuit from this ground is extended through the winding of relay 45' to the wiper 28 associated with the terminal bank 22 of the rotary switch X1, but this circuit has no effect until this wiper reaches the home position, and closes the circuit to relay 38.

At the time that relay 51 operated, the line circuit was traced from positive battery at the operator's set to the L wiper of the finder-connector switch W. From this point the line circuit extends through contacts A of cut-off relay 11, contacts of line jack 9, line 1, low resistance winding of the polar line relay 2 at the station set V, contacts of calling key 7, keyboard contacts 4, printer magnet 3, break key 8 to ground. Positive potential through the winding of the polar line relay 2 causes this relay to close its contacts and close an obvious circuit through the winding of the control relay 6. The control relay thereupon operates to close the circuits of the station motor 5 and to close a circuit which shunts the calling key contacts. When the station motor starts, the operator at the station restores the calling key 7, but this is without effect since this key is now shunted by contacts of the control relay 6. The subscriber's station printer is now connected through finder-connector switch W to the printer of the operator's set Z at the central office and telegraphic communication can be carried on over this circuit.

After the message has been transmitted, the central office operator releases the connection by operating the release key 64. This operation removes ground from the guard lamp 58 and switching relay 55 and from the winding of relay 44 at the finder-connector switch W. The switching relay 55 releases restoring the circuits of the operator's set to normal thereby applying negative battery to the station line 1. Relay 44 of the finder-connector switch W releases opening the circuit through the winding of relay 45. Relay 45 releases, transferring ground from the bank terminal 42D of the idle position selector switch X1 to the operator's idle lamp 15. Removal of this ground from the bank terminal 42D of the idle position selector switch makes the finder-connector switch W available for other incoming calls. The idle operator lamp 15, associated with the finder-connector switch W lights to inform the supervisor at U that the position is idle. Release of relay 45 also removes ground from the upper or high resistance winding of relay 51 so that this relay releases. Release of this

relay restores to normal the circuits previously traced through its contacts. One of these circuits now extends from ground through contacts A of relay 44, contacts H of relay 51, contacts A of relay 45, operated off-normal contacts C, winding of release magnet 49, winding of relay 107 to battery. The release magnet then operates restoring the switch mechanism to normal.

- 10 At the time that relay 51 released, ground was removed from the winding of cut-off relay 11, causing this relay to release. Release of cut-off relay 11 connects the line circuit 1 through the winding of line relay 10 to negative battery. Negative potential on the line (first from the operator's key 54 and then through the line relay 10) causes the polar line relay 2 at station V to open its contacts and thus release the control relay 6. Release of the control relay opens the circuit of the printer motor 5 and removes the shunt from the high resistance winding of the polar line relay 2. The inclusion of this high resistance in the line circuit will 25 reduce the line current to the normal "supervisory" or "idle" value which is insufficient to cause the operation of line relay 10. All circuits are, therefore, restored to normal.

29 Special features

An alarm is provided which will function in case a call is initiated and not carried to completion, either through failure of the operator to complete the dialling operation or through mechanical failure of the finder-connector switch. The operation of this alarm depends upon the operation of slow-operating dash-pot relay 104. The circuit for the winding of this relay extends through contacts A of relay 51 and contacts D of relay 45 to ground, and is multiplied to similar contacts of the other switches in the same group. Since relay 45 operates upon the initiation of call and since operation of relay 51 indicates the completion of the connection, it is evident that failure to establish a connection after relay 45 has been once operated would cause the energization of dash-pot relay 104. This relay may be adjusted to close its contacts after a length of time which would not elapse under normal operation of the switch. Closure of these contacts establishes obvious circuits through an alarm bell 110 and a lamp 119 to attract the attention 55 of the attendant, the lighted lamp indicating the shelf on which the switch is located.

Another alarm is provided to attract the attention of the attendant in case an inward call is not carried to completion because of failure of the idle position selector X or failure of the finder-connector switch. In such an instance, the group relay 20 would remain operated for an undue length of time and through the contacts of the group relay, relay 120 would be energized over an obvious

circuit. Operation of relay 120 closes a circuit from battery through the winding of dash-pot relay 121, contacts of relay 120 to ground through contacts B of relay 122. Since the winding circuit of relay 122 extends in series through contacts, such as A, of all of the chain relays, such as 21, it is evident that relay 122 will not be operated except in such instances where all switches of the system are busy and an inward call is waiting thus energizing a group relay, as 20. In this latter case it would not be desired to give an alarm. If one or more switches are idle, relay 122 will be unoperated and the circuit through the winding of the dash-pot relay 121 would remain closed during the length of time that an incoming call remained unanswered. Dash-pot relay 121 may be adjusted to close its contacts after a suitable length of time. Upon closure of these contacts obvious circuits are established through an alarm bell 123 and a lamp 124 to attract the attention of an attendant.

A green supervisory lamp 125 is provided which, when lighted, will inform the supervisor that all attended positions are busy. A red lamp 126 is provided which, when lighted, will inform the supervisor that all attended positions are busy and that a call is waiting. The circuit to the green lamp 125 is completed by the operation of relay 127. Relay 127, in turn, can operate only when all chain relays, such as relay 21, are released, which condition indicates that all the switches are busy. The circuit for the red lamp 126 is completed by the operation of relay 122 and, since this relay can operate only when all the chain relays, such as relay 21, are released and when the start-lead 117 is grounded, due to an additional incoming call, it is obvious that the red lamp 126 will light whenever all switches are busy and a call is waiting. An electric counter (not shown) may be provided to totalize the number of times this latter condition occurs. The circuit to the counter is completed by the operation of dash-pot relay 128. This relay is energized when relay 122 is operated, and may be adjusted to close the circuit to the counter after any desired interval of time, so that only those calls which have remained unanswered for this period of time will be registered. If desired, this counter may be associated with an electric clock circuit (not shown) which will close the counter circuit momentarily at definite intervals, say once per minute, so that the counter will record the total length of time such calls are held waiting.

Moreover, a relay 129, indicated in the start circuit 117 is provided to control, through its contact A, a counter (not shown) in order to indicate the total number of incoming calls.

60 A "make busy" key 14 is provided for each

finder-connector switch, such as switch W, so that the supervisor may, by operating this key, make the associated operator's set busy to all incoming calls. When this key is in the unoperated position the circuits extending through it provide for normal operation of the finder-connector switch. When this key is operated, a circuit from ground is extended through its A contacts to the corresponding bank terminal 42D in bank 25 of the idle position selector switch X1 so that the idle position selector cannot stop at this point. Also the operation of this key opens at its D contacts the ground from contacts B of relay 51 which extends to the chain relay 21, thus making the switch W busy to the chain relay, so that if all the other switches in the same group were busy, the chain relay would release transferring the start lead 117 to the next consecutive idle position selector. When the make-busy key is operated, the circuit to the idle operator lamp 15 associated with this switch is also opened, and ground is also removed from the winding of the control relay 59 at the operator's set Z but, since an additional ground extends to this relay from contacts F of the operator's key 54, the act of operating the make-busy key cannot in itself release the control relay. However, should the make-busy key be operated and the operator's key thrown to the right, the control relay 59 will release to remove line battery and motor power from this operator's set, so that the set can be completely shut down when not in use.

Precautions are taken to avoid trouble in case the calling key at an outside station is momentarily operated and then released before the finder-connector switch has time to complete its function. Assume that the calling key at station V is operated only for a length of time sufficient to cause the idle position selector to find an idle finder-connector switch, such as switch W, and to start this switch hunting. In this case the group relay 20 releases and removes ground from the vertical commutator so that the switch will hunt to the top level. It will be noticed that the top commutator terminal r1 is permanently grounded so that a switch will always cut in on this level and then start the rotary hunting. The pulsing circuit for the rotary magnet extends through eleventh rotary contacts 12 which open when the switch steps to the eleventh rotary position, so that at this time the pulsing circuit, which also, as previously traced, extends through a winding of relay 39 in locator X, is opened. The finder-connector switch W then comes to rest and relay 39 releases, restoring the idle position selector X to normal, as previously described. Relay 51 of the finder-connector switch will not be operated so the line connection to the printer at the associated operator's set Z is open. The operator, upon noticing

the open line condition, operates the release key 64, restoring the switch W to normal in the manner previously described.

It should be noted that in case of any trouble condition which prevents a switch from cutting in on the calling line, the switch will step to the top level, then around to the eleventh rotary position, and come to rest.

The foregoing description has been given in order to disclose a preferred embodiment of the present invention, and the subject matter contained therein is to be construed as broadly as the appended claims permit.

What is claimed is:

1. In an exchange system, a plurality of subscribers' stations, a first and a second switch, each adapted to connect with any one of said subscribers' stations, and means effective when said second switch attempts to connect with a subscriber's station to which said first switch is connected for indicating the identity of said first switch. 80

2. In an exchange system, a plurality of subscribers' stations, a first and a second switch, each adapted to connect with any of said subscribers' stations, and means effective when said second switch attempts to connect with a subscriber's station to which said first switch is connected for indicating the identity of said first switch and for giving a notification 95 that said first switch is to be held operated. 95

3. In an exchange system, a plurality of subscribers' stations, each connected to a central station having a first and a second operator's set, a printer at each set, a first switch associated with said first set, a second switch associated with said second set, each switch being adapted to extend a connection from the set associated therewith to any one of said subscribers' stations, and means effective 105 when the second set attempts to establish a connection to a subscriber's station connected to the first set, for causing the printer at the second set to print a character designating the first set. 110

4. In an exchange system, a plurality of subscribers' stations, each connected to a central station having a first and a second operator's set, a first and second switch respectively associated with said sets, each switch being adapted to extend a connection from the set associated therewith to any one of said subscribers' stations, and means effective when the second set attempts to establish a connection to a subscriber's station connected with 115 the first set, for indicating at the second set the identity of the first set. 120

5. In an exchange system, a plurality of subscribers' stations, each connected to a central station having a first and a second operator's set, a first and second switch respectively associated with said sets, each switch being adapted to extend a connection from the set associated therewith to any one of said subscribers' stations, and means effective 125 130

- when the second set attempts to establish a connection to a subscriber's station connected with the first set, for indicating at the second set the identity of the first set, and for indicating at said first set that the connection with said subscriber's station is to be maintained. 5
6. In an exchange system, a plurality of subscribers' stations, each connected to a central station having a first, second and third operators' sets, a first, second and third switch respectively associated with said sets, each switch being adapted to extend a connection from the set associated therewith to any one of said subscribers' stations, and means effective when the second and third sets attempt simultaneously to establish connection with a subscriber's station connected with the first set, for indicating first at the second set and then at the third set the identity of the first set. 10
7. In an exchange system, a plurality of subscribers' stations, each connected to a central station having a first, second and third operators' sets, a first, second and third switch respectively associated with said sets, each switch being adapted to extend a connection from the set associated therewith to any one of said subscribers' stations, and means, effective when the second and third sets attempt simultaneously to establish connection with a subscriber's station connected to the first set, for indicating first at the second set and then at the third set the identity of the first set, and for indicating at said first set that the connection with said subscriber's station is to be maintained until messages from the two other sets have been received. 15
8. In an exchange system, a plurality of subscribers' stations, each connected to a central station having a first and a second operator's set, a printer at each set, a first switch associated with said first set, a second switch associated with said second set, each switch being adapted to extend a connection from the set associated therewith to any one of said subscribers' stations, and means effective when the second set attempts to establish a connection to a subscriber's station connected to the first set, for causing an indication at the first set that the connection is to be maintained and an indication at the second set that the called subscriber's station is busy, and for causing the printer at the second set to print a number designating the first set. 20
9. In an exchange system, a plurality of subscribers' stations, each connected to a central station having a first and a second operator's set, a lamp bank, a first switch associated with said first set, a second switch associated with said second set, each switch being adapted to extend a connection from the set associated therewith to any one of said subscribers' stations, and means, effective when the second set attempts to establish a connection to a subscriber's station connected to the first set, for causing an indication at the first set that the connection is to be maintained and an indication at the second set that the called subscriber's station is busy, and for operating the lamp bank in accordance with the designation of the first set. 25
10. In an exchange system, a plurality of subscribers' stations, each connected to a central station having a first and a second operator's set, a printer at each set, a first switch associated with the first set, a second switch associated with the second set, each switch being adapted to extend a connection between the set associated therewith and any one of the subscribers' stations, a busy position locator associated with the switches, and means, effective when the second set attempts to establish a connection to a subscriber's station connected to the first set, for placing the printer at the second set under control of the busy position locator. 30
11. In an exchange system, a plurality of subscribers' stations, each connected to a central station having a first and a second operator's set, a printer at each set, a first switch associated with the first set, a second switch associated with the second set, each switch being adapted to extend a connection between the set associated therewith and any one of the subscribers' stations, a busy locator provided with transmitting means, associated with the switches, means effective when the second set attempts to establish a connection to a subscriber's station connected to the first set, for connecting the printer at the second set and the busy position locator and for starting the transmitting means, and means for placing the printer at the second set under control of the transmitting means when the latter has reached an operative condition. 35
12. In an exchange system, a plurality of subscribers' stations, each connected to a central station having a first and a second operator's set, a printer at each set, a first switch associated with the first set, a second switch associated with the second set, each switch being adapted to extend a connection between the set associated therewith and any one of the subscribers' stations, a busy position locator associated with the switches, said locator having transmitting means and groups of code relays associated therewith for predetermined the impulses to be transmitted by the transmitting means, means effective when the second set attempts to establish a connection to a subscriber's station connected to the first set, for connecting the printer at the second set and the locator, for starting the transmitting means and for operating relays corresponding to the first set in each of the code relay groups, and means for placing the printer at the second set under control of the transmitting means when the latter has reached operating speed. 40
13. In an exchange system, a plurality of 30

- subscribers' stations, each connected to a central station having a first and a second operator's set, a printer at each set, a first switch associated with the first set, a second switch 5 associated with the second set, each switch being adapted to extend a connection from the set associated therewith to any one of the subscriber's stations, a busy locator provided with transmitting means associated with the 10 switches, means, effective when the second set attempts to establish a connection to a subscriber's station connected to the first set, for connecting the printer at the second set and the busy locator and for starting the 15 transmitting means, and a plurality of counting relays responsive to the operation of the transmitting means for placing the printer at the second set under control of the transmitting means when the latter has reached 20 operating speed.

14. In an exchange system, a plurality of subscribers' stations each connected to a central station having a plurality of operators' sets, a switch individual to each set for extending a connection in either direction between the associated set and any one of the subscribers' stations, an idle position locator actuated whenever a call is initiated by one 25 of the subscribers' stations for selecting the first idle one of said switches and for then operating the selected switch to find the calling subscriber's line, and means effective when the calling line has been found for returning the idle position locator to a normal 30 position.

15. In an exchange system, a plurality of subscribers' stations, each connected to a central station having a plurality of operators' sets, a switch individual to each set for extending a connection in either direction between the associated set and any one of the subscribers' stations, an idle position locator having a normal position and a plurality of off-normal positions, and means for starting 40 the idle position locator only when it is in its normal position.

16. In an exchange system, a combination finder-connector switch, an alarm associated therewith, and means for operating the alarm 50 when the switch is started to find a calling line, but fails to operate completely.

17. In an exchange system, a first and a second operator's position, a line circuit associated therewith, means individual to each operator's position for connecting said position and said line circuit, and means for informing the first operator of the identity of the second operator's position when the first operator attempts to establish connection 55 with said line circuit when said circuit is connected with the second operator's position.

18. In an exchange system, subscribers' stations each connected to a central station provided with operators' sets, a switch, associated with each set, for extending a connec-

tion therefrom to any subscriber's station, a busy position locator and a lamp bank common to said sets, said locator being started when a set attempts to establish connection with a subscriber's line connected to another set, means for stepping said locator until it reaches the calling switch, and means responsive thereto for operating a hold indicating device at the calling and busy sets, and for operating said lamp bank in accordance with the designation of the busy set.

19. In an exchange system, subscribers' stations each connected to a central station provided with operators' sets, a switch, associated with each set, for extending a connection therefrom to any subscriber's station, a busy position locator and a lamp bank, common to said sets, said locator being started and a busy indicating device at the calling set being actuated when the calling set attempts to establish connection with a subscriber's line connected to another set, means for stepping said locator until it reaches the calling switch, and means responsive thereto for operating a hold indicating device at the calling and busy sets, and for operating said lamp bank in accordance with the designation of the busy set.

20. In an exchange system, a plurality of subscribers' stations each connected to a central office provided with operators' sets, each set having a printer, a printer motor and a relay effective upon its energization to close and upon its de-energization to open the power circuit of said motor, said relay having a normally closed operating circuit extending through a key at the set, combination switches for extending a connection in either direction between said sets and said subscribers' stations, an idle position locator associated with said switches, and a make-busy key individual to each set and located at a supervisory position, each key being normally positioned to complete another operating circuit for the relay at the associated set and to make said set selectable by said locator, each key being also positionable to open one operating circuit for the control relay at the associated set, thereby placing the printer motor under control of said set, and to make said set unselectable by said locator.

21. In an exchange system, a central station having a plurality of operators' sets, each having a printer, a printer motor and a control relay effective upon its energization to close and upon its de-energization to open the power circuit of said motor, a make-busy key individual to each set and located at a supervisory position, each make-busy key being normally positioned to complete an operating circuit for the control relay at the associated set, another operating circuit for said control relay extending through a key at said set, each make-busy key being also positionable to open one operating circuit for

the control relay at the associated set, thereby placing the printer motor thereat under control of the operator at said set.

22. In an exchange system, a central station having a plurality of operators' sets, each having a printer, a printer motor and a relay controlling the power circuit of said motor, and means individual to each set at a supervisory position for placing the relay at the associated set either under the joint control of the supervisory position and the set, or under the sole control of said set.

23. In an exchange system, subscribers' stations, each connected to a central station having operators' sets, a combination switch, associated with each set, for extending a connection in either direction between any subscriber's station and the associated set, an idle position locator for pre-selecting and then stepping the switch associated with the first idle set until it finds a calling line, a busy position locator for selecting a switch that has tested a busy called subscriber's line and for then indicating to the calling set the identity of the busy set in connection with the busy line, the extent of the rotary stepping of each switch when acting as a finder being controlled through a test wiper of the switch by a line relay associated with the calling line, and the identifying means in the busy position locator being controlled by a relay in the busy switch operated over a circuit including the test wipers of the calling and the busy switch.

24. In an exchange system, subscribers' stations, each connected to a central station provided with operators' sets, switches for extending a connection from said sets to said subscribers' stations, a busy position locator for successively selecting calling switches that have tested a busy called subscriber's line, an indicator common to said sets, said indicator being operable, when said locator selects each calling switch, to indicate the identity of the set in connection with the busy called line tested by the selected switch, and means at the set, associated with each calling switch and likewise operable upon the selection of said switch by the locator, for informing the operator thereat that the indication then appearing on said indicator identifies the set in connection with the line called by the calling set.

25. In an exchange system, subscribers' stations, each connected to a central station provided with operators' sets, switches for extending a connection from said sets to said subscribers' stations, a busy position locator for successively selecting calling switches that have tested a busy called subscriber's line, an indicator common to said sets, means in each busy switch for operating said indicator to indicate the identity of said switch, said means being responsive to the selection by said locator of the switch calling the line

connected to the busy switch, and means at the set associated with the selected calling switch and likewise operable upon said selection, for informing the operator thereat that the indication then appearing on said indicator identifies the set associated with the switch in connection with the busy called line.

26. In an exchange system, subscribers' stations, each connected to a central station provided with operators' sets, combination finder-connector switches for extending connections in either direction between said sets and said subscribers' stations, each switch being normally selectable by an idle position locator and unselectable by a busy position locator, means in each switch effective when the switch is seized by an operator's set for making the switch unselectable by said idle position locator, and additional means in each switch, effective when the switch has tested a busy called subscriber's line, for making said switch selectable by said busy position locator.

In witness whereof, I hereunto subscribe my name this 14th day of December 1931.

GILBERT S. VERNAM.
